Primary Examiner — Michael A. Pratt

(57) **CLAIM**

The ornamental design for a curtain rod, as shown and described.

DESCRIPTION

FIG. 1 is a front, right and top perspective view showing the four components of my new design separated one from the other.

FIG. 2 is a rear, left and bottom perspective view of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is an enlarged partial view of FIG. 1;

FIG. 10 is an enlarged partial view of FIG. 2;

FIG. 11 is a perspective view of the four components when assembled;

FIG. 12 is another perspective view of FIG. 11;

FIG. 13 is a front view of FIG. 11;

FIG. 14 is a rear view of FIG. 11;

FIG. 15 is a left side view of FIG. 11;

FIG. 16 is a right side view of FIG. 11;

FIG. 17 is a top plan view of FIG. 11;

FIG. 18 is a bottom plan view of FIG. 11;

FIG. 19 is a perspective view of the curtain rod of FIG. 11, shown in condition of use;

FIG. 20 is an enlarged partial view of FIG. 11; and,

FIG. 21 is an enlarged partial view of FIG. 14.

The broken lines in FIG. 19 showing a curtain depict environment only and form no part of the claimed design.

1 Claim, 21 Drawing Sheets
